UNITED STATES PATENT OFFICE.

CHRISTIAN FLECK, OF OHLIGS, GERMANY.

KNEADING-MACHINE.

SPECIFICATION forming part of Letters Patent No. 635,310, dated October 24, 1899.

Application filed April 7, 1899. Serial No. 712,059. (No model.)

To all whom it may concern:

Be it known that I, CHRISTIAN FLECK, a subject of the Emperor of Germany, residing at Ohligs, Germany, have invented certain new and useful Improvements in Kneading-Machines, of which the following is a specification.

My invention consists of a tank or receptacle in which two shafts are supported at opposite inclinations, and said shafts are provided with agitating-arms arranged in different horizontal planes and rotating with their respective shafts so that they cross each other's paths, of a peculiarly-formed bottom for said tank, of giving a peculiar form to the agitating-arms and adapting them to travel in lines parallel to the aforesaid bottom, and in the provision of other details useful and novel, as will be fully described.

20 In the accompanying drawings, forming a part of this application, Figure 1 is a vertical longitudinal section of my invention complete on a central line. Fig. 2 is a vertical cross-section on line *i i* of Fig. 1. Fig. 3 is a top plan view of the machine.

Referring to the drawings, A represents a tank or receptacle suitably mounted on a base M'.

B and C represent, respectively, shafts set 30 at an inclination toward each other and located in the central longitudinal plane of the tank. Said shafts pass through and are guided at their lower parts in suitable bearings in the bottom D, and at their upper ends have 35 bearings in openings in a bar E, arranged transversely of the tank. The shafts B and C are rotated by a drive-shaft F, which is journaled in suitable bearings X X' on the cross-bar E and has keyed to one end a fly- 40 wheel N and may be driven by hand or any suitable power. The rotation of said shaft F is transmitted to the shafts B and C by means of a bevel gear-wheel G on the shaft F, G' on the upper end of the shaft B, meshing with the gear G, and gear-wheels H H', 45 fixed on the lower ends of the shafts B and C, respectively, and having their teeth intermesh, whereby the shafts are rotated in opposite directions.

50 Q represents a metal or other suitable casting, within which the gear-wheels G G' are housed.

Each of the shafts B and C carries a series of agitating and kneading arms, preferably arranged in pairs and curved, as J and K. 55 Said arms are arranged one above the other upon their respective shafts, so that the two series when rotated will cross each other's paths between the shafts. Said arms are of such length that the arms of one series are 60 brought close to the shaft of the second series, but without striking same, and are bent or curved convex to the direction of rotation. The arms are arranged at such angles to their respective shafts that they travel in a horizontal plane and so that the upper arm of one series passes over the lower arm of the other series.

The bottom D is suitably secured to the walls of the tank and slopes downwardly and 70 inwardly toward the shafts B and C, while the portion between said shafts is horizontal.

The upper arm K of each series of agitators carries at its outer end an extension or blade L, set at an acute angle to said arm, said blade 75 serving to detach the paste from the shaft upon the rotation of the arm, whereby the paste is effectively prevented from being twisted around said shaft.

A door M is provided in the front wall of 80 the tank A, through the way of which the completed paste is removed from the tank. Said door may be locked by means of a screw W or its equivalent.

The apparatus above described is used by 85 placing the materials to be kneaded into the tank and the arms rotated. The peculiar shape of the arms serves to drive the materials toward the walls of the tank, while the shape of the bottom D tends to throw them 90 toward the center, thus thoroughly mixing and kneading the materials.

Having thus described my invention, what I claim as new, and desire to secure by Letters Patent, is—

1. A kneading-machine comprising a tank, inclined shafts mounted in a vertical plane in said tank, means for rotating said shafts in opposite directions, a bottom having downwardly and inwardly inclined sides secured 95 to said tank, agitating-arms secured to said shafts and adapted to rotate parallel with the said bottom, and provided with angularly-arranged extensions, as described.

2. A kneading-machine comprising a tank, inclined shafts mounted in a vertical plane in said tank, means for rotating said shafts in opposite directions, a bottom having downwardly and inwardly inclined sides secured in said tank, arms curved convex to the direction of their movement, mounted on said shafts in different horizontal planes and adapted to rotate parallel with said bottom, as set forth.

3. A kneading-machine consisting of a tank, inclined shafts mounted in a vertical plane in said tank and carrying on their lower ends intermeshing toothed wheels, and one of said

shafts carrying on its upper end a bevel-pinion, a drive-shaft, a bevel-pinion on said drive-shaft and meshing with a like pinion on the inclined shaft, a bottom having downwardly and inwardly inclined sides and horizontal central portion, arms secured to said shafts and curved convex to the direction of their movement, said arms being adapted to rotate parallel to said bottom, and angular extensions on said arms, substantially as set forth.

CHRISTIAN FLECK.
